UNITED STATES PATENT OFFICE

DAVID A. BENBOW AND GEORGE KUNZ, OF DAYTON, OHIO, ASSIGNORS TO FRIGIDAIRE CORPORATION, OF DAYTON, OHIO, A CORPORATION OF DELAWARE

TUBE FLARING APPARATUS

Application filed April 28, 1932. Serial No. 608,051.

This invention relates to an apparatus for and a method of forming a flare on the end of a tube.

It has heretofore been customary to drive or force a suitably shaped tool into the end of a tube or conduit to flare the metal at the end of the tube or conduit outwardly against a stop member, removably clamped around the body of a tube and of such form as, to 10 provide a flare of the desired shape and size on the end of the tube. Such practice has not been entirely satisfactory because the operator, upon striking the tool to drive the same into the end of the tube, has not held the tool, 15 nor has he been able to determine if the tool is held, in perfect alignment with the longitudinal center of the tube. Therefore when the tool is driven into the end of the tube out of alignment of the center thereof, the tool bears unevenly against one wall portion of 20 the tube and causes that portion of the wall to engage the stop portion of the member, clamped around the tube, before other portions of the tube wall not to be flared outwardly the required distance. 25 This causes the thickness of one portion of the wall of the tube to be deformed while at the same time causing other portions of the tube wall not to be flared outwardly the required distance. A flare made according to the foregoing 30 mentioned method can not be clamped evenly or clamped with a uniform pressure throughout its circumference by clamping nuts at connections desired in conduits or tubes thus resulting in leaks at such joints or 35 connections in piping systems provided by the tubes. It has also been found that flares formed in tubes according to the foregoing mentioned method quite frequently causes the metal at the end of the tube to crack or 40 break apart, due to the metal of the tube being crystallized, thus rendering the tube unsuitable for use.

An object of the present invention is to provide an improved method of and apparatus for forming a flare on the end of a tube or conduit which flare will be of uniform thickness throughout its circumference and concentric relative to the longitudinal center of the tube or concentric with the diameter of 50 the tube at the end thereof.

In carrying out the foregoing object it is a further object of the present invention to provide an improved apparatus having means which rolls the metal at an end of a tube outwardly to form a flare to which a 55 predetermined uniform pressure can be applied throughout the entire circumferential wall portion of the flare when the tube is connected in a piping circuit or system.

Further objects and advantages of the invention will be apparent from the following description, reference being had to the accompanying drawings, wherein a preferred form of the present invention is clearly shown.

In the drawings:

Fig. 1 discloses a top plan view of a tube flaring apparatus constructed according to the present invention;

Fig. 2 is a side elevational view of the apparatus shown in Fig. 1;

Fig. 3 is an enlarged longitudinal vertical sectional view of the apparatus taken on the line 3-3 of Fig. 1;

Fig. 4 is a view similar to Fig. 3 but showing the apparatus in a different position;

Fig. 5 is a vertical sectional view through the apparatus taken on line 5-5 of Fig. 3 showing the tube receiving device;

Fig. 6 is a vertical sectional view through the apparatus taken on the line 6-6 of Fig. 3 showing the clutch mechanism thereof;

Fig. 7 is a vertical sectional view through the apparatus taken on the line 7-7 of Fig. 3 showing the connection between the driving member and the tube flaring element of the apparatus;

Fig. 8 is a vertical section through the spindle carrying member of the apparatus taken on the line 8-8 of Fig. 3;

Fig. 9 is a fragmentary sectional view similar to Fig. 6 showing parts of the clutch mechanism in a disengaged position; and

Fig. 10 is a view of the tube receiving opening of the apparatus looking in the direction of the arrow 10 in Fig. 3.

Referring to the drawings there is shown one form of an apparatus suitable for carrying out the invention comprising an upper casing 25 and a lower casing 26 secured to 100

gether to form an enclosure for parts of the apparatus to be hereinafter described. A shaft 27 journaled in bearings provided in the walls of the casings 25 and 26 extends outwardly from the enclosure and has a pulley 28 mounted thereon (see Figs. 1, 2, 3 and 7). The pulley 28 is located exteriorly of the enclosure and is adapted to be driven or rotated by any suitable driving means (not shown). A small spiral gear 29 keyed on shaft 27 within the enclosure meshes with a relatively larger spiral gear 31 (see Figs. 3, 4 and 7). Gear 31 is secured against rotation relative to a shaft 32 by a key 33 and consequently rotates the shaft 32. However, the arrangement of key 33 permits longitudinal movement of the shaft 32 relative to gear 31. Gear 31 has an outwardly extending shank portion 34 formed thereon and which shank has a worm 35 formed on the end thereof. Worm 35 meshes with a ring gear 36 (see Figs. 3, 4 and 6) secured by a pin 37 to a shaft 38 which shaft is journaled in bearings provided in the walls of casing 26. Gear 36 has a hardened steel ring 39 firmly fastened thereto which ring is provided with a plurality of holes or openings 41. A plurality of hardened steel pins 42 are secured to a member 43 surrounding shaft 38 and spaced from the ring 39 by a cam 44 also surrounding shaft 38 and through which the pins 42 pass. A spring 45 located between the member 43, which carries the pins 42, and the inner surface of the wall of casing 26 normally holds and forces pins 42 into the openings 41 on ring 39. However, member 43 has formed thereon a camming surface 46 adapted to engage a vertically movable peg 47 for moving the pins 42 simultaneously with member 43 longitudinally relative to gear 36, and ring 39 secured thereto, for causing disengagement of the pins 42 from the openings 41 in ring 39 (see Fig. 9). The parts designated by the numerals 39, 41, 42, 43 and 46 thus provide a clutching mechanism for stopping and starting rotation of the cam 44. When cam 44 is disengaged from its driving connection with the shaft 38 or gear 36 the shaft 38 freely rotates therein. Peg 47 is mounted in a suitable socket or bracket 48 and is normally held in a position to engage the camming surface 46 of member 43 by springs 49 and 50. Spring 49 bears against a shoulder formed on peg 47 and also against the inner wall surface of casing 25. The upper end 51 of peg 47 extends through the top wall of casing 25 and is engaged by a forked end of an arm 52 pivotally mounted on casing 25 as at 53. The opposite end of arm 52 is connected to a downwardly extending rod 54 which rod is attached to a foot pedal arm 55 in any suitable well known manner. The spring 50 surrounds the rod 54 and applies its tension

to this rod by having its ends clamped between any suitable rigid members one of which is on the rod and the other of which may be stationary. Thus the parts designated by the numerals 47, 48, 49, 50, 52, 53, 54 and 55 comprise a lock or lever mechanism for rendering the clutching mechanism effective or ineffective.

The cam 44 rotates between a pair of horizontally disposed rollers 61 mounted on shafts 62 (see Figs. 3 and 4) which shafts are journaled in a casting 63 located within the enclosure formed by the casings 25 and 26. The casting 63 comprises a forked portion between the legs of which fork the cam 44 rotates (see Fig. 6). The legs of the forked portion of casting 63 are shaped to pass under the shaft 38 and the members mounted thereon in order to support the rollers 61 on opposite sides of shaft 38 and in alignment with the center thereof and with the center of the cam 44. The casting 63 has an upwardly extending hollowed out portion 64 which surrounds an enlarged portion of shaft 32 and is secured thereto to move longitudinally with this shaft. The enlarged portion of shaft 32 is clamped to the hollowed out portion 64 of casting 63 by clamping nuts 32a which clamp the portion 64 of casting 63 between a washer 32b and a ball-bearing 32c which bears against a shoulder 32d formed on the shaft 32. Casting 63 also comprises another hollowed out portion 65 which receives an end 66 of a shaft 67. A wall of the hollowed out portion 65 of casting 63 is split as at 68 (see Figs. 3 and 4) and a bolt 69 passes through the metal of casting 63 at this split portion in order to firmly clamp the hollowed out portion 65 to the end 66 of shaft 67. Shaft 67 is mounted in and passes through a bearing 71 formed in the lower portion of casing 26 within the enclosure. The casings 25 and 26 each have hollowed out portions which portions, when the casings are bolted together form bearings 73 and 74 for the shaft 32. The bearing 74 is disposed directly above the bearing 71 in shaft 67.

Shaft 32 has its one end hollowed out as at 76 and receives therein a shank portion 77 formed on a member 78 (see Figs. 3 and 4). This shank portion 77 of member 78 is keyed to the shaft 32 to rotate therewith by a pin 79 in any suitable manner. Preferably the shank 77 is keyed to the shaft 32 so as to afford a slight longitudinal movement of member 78 relative to shaft 32. A spring 81 located in the hollowed out portion 76 of shaft 32 is interposed between the end of the shank portion 77 and the end of the hollowed out portion 76 to normally force shank portion and member 78 outwardly of shaft 32. The member 78 is mounted in a housing 83 and is adapted to rotate therein due to its connection with the shaft 32 as described.

Housing 83 forms a bearing on one side thereof for the member 78 and has a plurality of slots in its opposite side which side is threaded upon a bearing member 84 through which member 78 extends. A split band member 85 extends around housing 83 at the threaded connection thereof with bearing member 84 and is tightly clamped by the bolt 86 to the bearing member 84. The lower portion of band member 85 is keyed to the housing 83 by a pin 87 and is also hollowed out as at 88 in order to permit the band member to straddle the shaft 67 and thereby prevent rotation of housing 83 (see Fig. 3). Member 78 has two angularly disposed hollowed out portions 91 provided therein (see Figs. 3, 4 and 8). A hole 92, having its center disposed at an angle relative to the longitudinal center of member 78, extends from each of the hollowed out portions 91 to the exterior of member 78. Holes 92 form bearings for a pair of shaft members or spindles 93 each of which spindles have a tapered end portion 94 extending outwardly from the member 78. The opposite ends 95 of shaft members or spindles 93 extend outwardly from the holes 92 into the hollowed out portions 91 provided in member 78. The ends 95 of spindles 93 each have a roller 96 mounted thereon by a lock nut and are keyed to the spindles by pins 97 which pins extend through the ends 95 and into slots 98 provided in the rollers 96. The outer cylindrical edge of each of the rollers 96 is tapered as at 99 and adjustable screws 101 locked to member 78 bear against the ends 95 of spindles 93 to force the tapered edge 99 of rollers 96 into tight frictional engagement with a corresponding tapered cylindrical surface 102 formed on the inner wall of housing 83 (see Figs. 3, 4 and 8). This engagement of surfaces 99 on rollers 96 with the cylindrically tapered surface 102 on housing 83 causes rotation of rollers 96 and consequently spindles 93 relative to the member 78 during rotation of member 78. Thus the spindles 93 rotate about an axis disposed at an angle to the axis of rotation of member 78 in which the spindles 93 are carried while the spindles 93 revolve about the longitudinal axis of the member 78.

A means for receiving an end of a tube or conduit and for clamping the tube against rotation while being held concentric with or in alignment with the longitudinal center of the rotatable member 78 is mounted adjacent the tapered ends 94 of spindles 93 (see Figs. 3, 4 and 5). This means comprises two superimposed members 111 and 112. These members 111 and 112 are separable from each other on a horizontal plane corresponding to the longitudinal center of member 78 and shaft 32. The upper member 111 has a semi-concaved cut-out portion 113 formed therein adapted to receive a similarly shaped hardened steel piece 114 which is securely fastened to member 111 by a screw or the like 115. The lower member 112 has a semi-circular convexed cut-out portion 117 formed therein adapted to receive a similarly shaped hardened steel piece 118 which is securely fastened to member 112 by a screw or the like 119. The two hardened steel pieces 114 and 118 cooperate when the members 111 and 112 are held or forced together, to form a cylindrical opening adapted to receive the end of a tube or conduit designated by the dot and dash lines 121 shown in Figs. 3 and 4 of the drawings. Each edge of the steel members 114 and 118 forming the cylindrical opening for receiving the tube 121 are tapered as at 122 outwardly from the opening. The tapered edge adjacent the spindles 93 is for a purpose to be hereinafter more fully described while the tapered edge located on the opposite side of members 114 and 118 serves to permit the tube 121 to be readily inserted into the openings. The members 111 and 112 are carried in vertical alignment by a casting 125 which casting is provided with an opening 126. Opening 126 in casting 125 includes an upper semi-cylindrical portion 127 having a radius equal to and located on the same plane as the radius of the central opening formed by the steel members 114 and 118. The lower portion 128 of opening 126 is of a greater diameter or radius than its upper portion (see Figs. 3, 4 and 10) and is for a purpose to be hereinafter more fully described. Clamping members 131 extend vertically along each edge of the upright portion of casting 125 and are secured to the casting 125 by bolts 132 (see Fig. 5). These clamping members 131 prevent horizontal movement of the members 111 and 112 while at the same time tending to firmly clamp these members 111 and 112 to the casting 125. The clamping members 131 or any other suitable means may be employed to secure member 111 stationary relative to casting 125.

The apparatus includes means for alternatively moving the lower member 112 vertically relative to the upper member 111. This means for alternatively moving member 112 up and down relatively to member 111 comprises a tongue 134 secured by any suitable means such as by the bolt 135 to the end of shaft 67 which shaft is grooved to receive the same. The tongue 134 has a raised portion 136 and tapered portions 137 and 138 formed on its upper edge which portions provide a cam. A roller 141 is mounted in an opening 142, provided in member 112, by shaft 143 and this roller is adapted to engage the cam or portions 136 and 138 of tongue 134. When the tongue 134 is moved horizontally roller 141 engages and rotates upon either the tapered surface 138 or raised portion 136 of tongue 134 due to the weight of

member 112 which weight is augmented by any suitable number of springs 133 (see Fig. 5).

When the end of a tube or conduit to be flared is inserted in the opening, formed by the complementary hardened steel pieces 114 and 118, it is desirable to insure that the apparatus will receive a predetermined length only of the end of the tube. This therefore insures that the portion at the end of tubes to be flared or deformed by the apparatus will be uniform in length. To effectively carry out this desirability of requirement the apparatus includes a stop member 145 movably held in a vertical position, on the side of the member 112 facing the spindles 93, by a cross piece 146 stationarily mounted in any suitable manner upon the member 112 (see Figs. 3, 4 and 5). This stop member 145 is adapted to be moved upwardly so as to block the passage of a tube, during insertion of the end thereof, through the opening formed by the hardened steel pieces 114 and 118. Stop member 145 is also adapted to be moved downwardly out of the path of the tapered walls 94 of spindles 93 so that the tapered portions 94 of spindles 93 may be brought into engagement with the end of the tube member to be flared. Therefore stop member 145 has a nose portion 147 formed at its lower end which nose portion is adapted to engage the tapered portion 137 or raised portion 136 provided on tongue 134 (see Figs. 3 and 4). An opening 148 in stop member 145 is located directly above the nose portion 147 formed thereon and is adapted to receive the end of a finger 151 provided on a member 152 which member is mounted on the tongue 134 at its connection with shaft 67. The nose portion 147 on stop member 145 is shaped to be received in the space provided between finger 151 on member 152 and the tapered portion 137 of tongue 134 in order to permit the tapered bottom edge of finger 151 to cam or move the stop member 145 downwardly. When the raised portion 136 of tongue 134 moves away from roller 141 it engages the bottom edge of nose 147, on stop member 145, and thus causes stop member 145 to be raised or elevated into a position to block the passage of a tube to be flared through the opening formed by the members 111 and 112. A pin 153 secured to casting 125 passes through an opening 154 provided in member 112 and extends through an opening 155 provided in stop member 145. Pin 153 serves to retain stop member 145 in assembled relation with member 112 during adjustment or removal of casting 125 from the apparatus.

The upright extending portion of casting 125 is formed integrally with a base portion 161 which is adjustably or removably secured to an outwardly extending portion 162 on casing 26. One or more fastening means such

as the bolt 163 which pass through an opening provided in a tapered side wall clamping member 164 is threaded in base 161 is employed for rigidly securing the casting 125 to the casing 26 (see Fig. 5). Base 161 of casting 125 has a hook portion 165 formed thereon and extending upwardly (see Figs. 3 and 4). A hardened steel angle iron member 166 is secured by screws 167 to the hook portion 165 of base 161 and serves to maintain the tongue 134 in alignment with the shaft 67 and in alignment with the shaft bearing 71. A square headed hardened stud 169 secured to base 161 and upon which the tongue 134 slides aids angle iron member 166 in its function of aligning the tongue 134 and shaft 67 with bearing 71 while at the same time serving to maintain the member 112 in vertical alignment. An adjustable stop stud 171 threaded into an upwardly extending portion 172 formed on casing 26 regulates and spaces the casting 125 and consequently members 111 and 112 at desired distances from spindles 93 to insure against deforming or changing the thickness of the outwardly flared wall of tube. The essential elements or parts of the apparatus having been described and enumerated it is to be understood that the apparatus also includes various other parts or elements necessary for the successful operation of the apparatus such for example as pins, bushings, plugs and stops or the like not described in detail but ordinarily employed in the production of such apparatus. It is to be also understood that means for lubricating the various rotating, sliding or operating elements of our apparatus may be provided in the well known manner to those skilled in the art.

Operation

Before proceeding with an explanation of the operation of the apparatus it is desired to first point out that when the apparatus is placed in operation the driving means connected with the pulley 28 may operate continuously or may be intermittently operated to cause rotation of shaft 32 and member 78 secured thereto. It is to be understood that the clutching mechanism including the elements designated by the reference characters 39, 41, 42, 43, 45 and 46 is effective only for moving the housing 83, shaft 32 and member 78 and consequently spindles 93 longitudinally relative to the members 111 and 112 which members receive the end of the tube to be deformed or flared outwardly. It is obvious therefore that as long as the apparatus is being operated by the driving means connected to the pulley 28, shaft 32, member 78 and spindles 93 will rotate irrespective of the longitudinal position thereof.

Assuming then that shaft 32, member 78 and parts attached thereto and adapted to move longitudinally therewith are in the po-

sition shown in Fig. 4 of the drawings when the apparatus is put into operation. The driving means connected to the pulley 28 causes this pulley to rotate and likewise shaft 27 and the gear 29 since gear 29 and pulley 28 are keyed to this shaft. Gear 29 rotates gear 31 and consequently worm 35 formed on the shank portion 34 of gear 31. Shaft 32, being keyed by the key 33 to worm 35 and gear 31, upon being rotated rotates member 78 and the spindles 93. Worm 35 causes rotation of gear 36 and shaft 38 to which gear 36 is secured. However, since the operator has not as yet pressed on the foot pedal or lever 55, peg 47 remains in engagement with the camming surface 46 formed on member 43 and thereby maintains the pins 42 out of engagement with the openings 41, provided in washer 39 secured to gear 36. Thus the clutching mechanism is in the position shown in Fig. 9 of the drawings and prevents longitudinal movement of the shaft 32, member 78 and spindles 93 until the operator actuates the foot pedal 55.

During operation of the apparatus as just described the tube receiving means or device of the apparatus comprising the members 111 and 112 are separated or are in open position while the stop member 145 is in raised position. The operator may therefore pass a tube into the opening 126 in casting 125 and into the opening provided in members 111 and 112 until the end of the tube strikes the stop member 145 as indicated by the dot and dash lines in Fig. 4 of the drawings. The apparatus may now be operated to cause the end of the tube to be deformed or flared outwardly. Foot pedal lever 55 is pushed downwardly by the operator and carries rod 54 therewith to move the end of arm 52, located on the side of pivot point 53 opposite from rod 54, upwardly. This movement of arm 52, which arm engages the upper end 51 of peg 47, causes peg 47 to also move upwardly and be disengaged from the camming surface 46 on member 43. Member 43 upon being disengaged from the peg 47 is moved horizontally by the force of spring 45 and moves the ends of pins 42 into the openings 41 provided in the washer member 39 rigidly secured to the gear 36 as shown in Fig. 6 of the drawings. Since pins 42 pass through the cam 44 this cam will be rotated thereby and by gear 36 when the pins 42 slip into the openings or holes 41. The cam 44 is thus caused to revolve between the rollers 61 to move the rollers 61 and consequently the casting 63 longitudinally. Obviously the longitudinal movement of casting 63 also moves shaft 67, tongue 134, finger 151, shaft 32, member 78, housing 83 and consequently spindles 93 longitudinally as shown in Fig. 3 of the drawings. This movement forces rollers 141 upwardly on the tapered surface 138 and onto the surface 136 of tongue 134 and simultaneously forces stop member 145 down, out of the path of the spindles 93, by engagement of the stop member with the tapered surface 137 of tongue 134 and by engagement of the finger 151 of member 152 with the opening 148 located above the lower end of nose 147 of stop member 145. Roller 141 therefore causes the members 114 and 118 to close against the members 111 and 114. Closing of these members forces the tube, which is at this time located therebetween, against the upper wall of the small portion 127 of opening 126 in casting 125 (see Fig. 3). The members 114 and 118 are so proportioned that they firmly clamp the tube against rotation without causing deformation thereof. Immediately after the members of the tube receiving device of the apparatus have been moved into the position just described the tapered ends 94 of spindles 93 come into engagement with the end of the tube. The spindles 93 are rotating at this time about an axis disposed at an angle to the axis of rotation of the member 78 or are rotating about an axis disposed substantially parallel to the tapered portions 122 on the members 114 and 118. The rotating tapered ends 94 of spindles 93 therefore roll or spin a flare on the end of the tube while the spindles are being revolved about the axis of the longitudinal center of the tube.

The rotation of member 78 and the rotation and revolutions of spindles 93 are governed or timed relative to rotation of cam 44, which cam moves the member 78 and spindles 93 longitudinally, to insure that when the cam 44 moves the spindles 93 away from the end of the tube, as shown in Fig. 4 of the drawings, this tube will be evenly deformed to provide a flare on the end thereof of uniform thickness throughout its circumference. Should the thickness of the wall of one tube vary relative to the thickness of the wall of other tubes, shank 77 on member 78 will be moved back, against the pressure exerted by spring 81, into the hollowed out portion 76 provided in shaft 32. Thus the spring 81 insures that the apparatus will apply a predetermined pressure only upon the end of the tube to be flared. It is to be understood that when the operator moves the foot pedal lever 55 downwardly and then immediately releases the same it releases the lock which maintains the clutching mechanism ineffective and renders the clutch mechanism effective for one revolution only of the cam 44. However, the operator may hold the foot pedal down indefinitely if desired to cause more than a single rotation of the cam 44 and consequently more than a single horizontal movement of shaft 32, member 78 and spindles 93. In either event the springs 49 and 50 tend to force the peg 47 downwardly into a position where it will be engaged by the cam surface 46 of member 43 as member 43

- rotates and will therefore disengage the clutch or will again render it ineffective for moving the member 78 and spindles 93 longitudinally when the foot pedal is released.
- 5 The clutching mechanism is designed to cause the longitudinal movement of member 78 and spindles 93 to stop in the position shown in Fig. 4 of the drawings. From the foregoing description and by reference to Fig.
- 10 4 of the drawings it will be seen that the apparatus is in a position to permit the tube which has been flared to be removed from the apparatus and to permit another tube to be placed therein to be flared.
- 15 The members 111 and 112, forming the tube supporting device of the apparatus, being separated as shown in Fig. 4 of the drawings permits the tube and its flared end to be removed from the opening provided in the
- 20 members 111 and 112. Removal of the flared ended tube from the apparatus is accomplished by moving the body of the tube extending through the small portion 127 of opening 126 in casting 125 downwardly into the larger portion 128 of opening 126 which
- 25 larger opening permits the flared end of the tube to freely pass therethrough. After the flared ended tube has been removed from the apparatus and while the apparatus is in the
- 30 position shown in Fig. 4 of the drawings another tube may be inserted, by the operator, into the opening 126 and into the tube receiving opening provided in members 111 and 112. The tube is pushed through the
- 35 openings until its end strikes member 145 which member is at this time in its upper position tending to block the passage of the tube through the openings a greater distance than is required. Obviously the operation
- 40 hereinbefore described can be repeated as desired to form a flare on the end of a plurality of tubes with greater speed than has heretofore been carried out with previously known methods. It is to be understood that
- 45 while an apparatus comprising two spindles is disclosed an apparatus including a single spindle may be employed. The use of an apparatus including two or more spindles is preferable because the metal at the end of
- 50 the tube, not engaged by a spindle, will not be deformed, as much as with the use of a single spindle, while the spindles are rolling or spinning other portions of the end of the tube over and outwardly to form a flare.
- 55 The use of two spindles is also preferable in order to avoid crystallizing the metal of the tube at the flared end.
- From the foregoing it is apparent that an improved apparatus for and an improved
- 60 method of forming a flare on the end of a tube has been provided. The improved apparatus due to rotation of the spindles and revolutions thereof during their travel inwardly of the end of the tube gradually rolls
- 65 or spins the metal at the end of the tube out- wardly and this gradual rolling or spinning method of deforming the end of the tube prevents the metal of the tube from splitting or cracking or being crystallized. The im- 70 proved apparatus furthermore insures that the metal of the flare on the end of the tube will be uniform in thickness throughout its circumference and that the flare will be concentric relative to the longitudinal center of the length of tubing or concentric with the cross-sectional diameter of the tube at its end. Thus the difficulties heretofore enum- 75 erated with respect to other methods of forming a flare on the end of a tube are elim- inated by the improved apparatus disclosed. 80
- While the form of embodiment of the in- 85 vention as herein disclosed, constitutes a pre- ferred form, it is to be understood that other forms might be adopted, all coming within the scope of the claims which follow. 85
- What is claimed is as follows:
1. An apparatus of the character de- 90 scribed comprising in combination, means adapted to receive a portion of a tube, a mem- ber disposed in alignment with and rotatable about the axis of the tube receiving portion of said means, means for rotating said mem- ber, means carried by said member and mov- 95 able longitudinally relative to said first named means, means for moving said last named means relative to said first named means during rotation of said member, and means for rotating said third named means about an axis disposed at an angle to the axis of rotation of said member during movement of the third named means relative to said first named means for spinning the wall of said tube outwardly at the end thereof. 100
2. An apparatus of the character de- 105 scribed comprising in combination, means adapted to receive a portion of a tube, a mem- ber disposed in alignment with and rotatable about the axis of the tube receiving portion of said means, means for rotating said mem- 110 ber, means carried by said member and rotatable relative thereto, said third named means and said member being mov- 115 able longitudinally relative to said first named means, means for simultaneously moving said member and said third named means relative to said first named means during rotation of said member, and means for rotating said third named means about an axis disposed at an angle to the axis of rotation of said member during movement of said member and said third named means relative to said first named means for spin- 120 ning the wall of said tube outwardly at the end thereof. 125
3. An apparatus of the character de- 125 scribed comprising in combination, means adapted to receive a portion of a tube, a mem- ber disposed in alignment with and rotat- able about the axis of the tube receiving por-

- tion of said means, means carried by said member and rotatable relative thereto, said second named means being movable longitudinally relative to said first named means, 5 means for simultaneously rotating said member and for moving said second named means relative to said first named means, and means for rotating said second named means about an axis disposed at an angle to the axis of rotation of said member during movement of said second named means relative to said first named means for spinning the wall of said tube outwardly at the end thereof. 10
- 15 4. An apparatus of the character described comprising in combination, means adapted to receive a portion of a tube, a member disposed in alignment with and rotatable about the axis of the tube receiving portion of said 20 means, means carried by said member and rotatable relative thereto, said second named means and said member being movable longitudinally relative to said first named means, means for rotating said member and for 25 simultaneously moving said member and said second named means relative to said first named means during rotation of said member, and means for rotating said second named means about an axis disposed at an angle to the axis of rotation of said member during movement of said member and said second named means relative to said first named means for spinning the wall of said tube outwardly at the end thereof. 30
- 35 5. An apparatus of the character described comprising in combination, means adapted to receive a portion of a tube, a member disposed in alignment with and rotatable about the axis of the tube receiving portion of said 40 means, means for rotating said member, a plurality of spindles carried by said member and rotatable relative thereto about an axis disposed at an angle to the axis of rotation of the member, said spindles being movable longitudinally relative to said first named means, and cam means for causing said spindles to move relative to said first named means during rotation of said member for expanding the wall of said tube outwardly at the end thereof. 45
- 50 6. An apparatus of the character described comprising in combination, means adapted to receive a portion of a tube, a member disposed in alignment with and rotatable about the axis of the tube receiving portion of said means, means for rotating said member, a plurality of spindles carried by said member and movable longitudinally relative to said first named means, cam means for causing 55 said spindles to move relative to said first named means during rotation of said member, and means for rotating said spindles about an axis disposed at an angle to the axis of rotation of said member during movement of the spindles relative to said first 60
- 65 named means for spinning the wall of said tube outwardly at the end thereof.
7. The method of forming a flare on an end of a tube member by engagement thereof with an element carried by another member which consists in, rotating one of said members and revolving the element about an axis common to both of said members while simultaneously rotating the element about an axis disposed at an angle to the axis of both of said members, and moving one of said members toward the other of said members to cause the element to engage the tube and to expand the wall of the tube outwardly 70
- 75 at the end thereof. 80
8. The method of forming a flare on an end of a tube by engagement thereof with an element carried by a rotatable member which consists in, holding the tube against rotation, rotating the member and revolving the element about an axis common to the longitudinal center of the tube while simultaneously rotating the element about an axis disposed at an angle to the longitudinal center of the tube and the axis of said member, and moving the member toward the tube to cause the element to engage the tube and to expand the wall of the tube outwardly at the end thereof. 85
9. The method of forming a flare on an end of a tube by engagement thereof with a spindle which consists in, holding the tube against rotation, revolving the spindle about an axis aligned with the longitudinal center of the tube while simultaneously rotating the spindle about an axis disposed at an angle to the longitudinal center of the tube, and moving the spindle into engagement with the inner wall of the tube to expand the wall of the tube outwardly at the end thereof. 90
10. An apparatus of the character described comprising in combination, means adapted to receive a portion of a tube, means revolvable about the axis of the tube receiving portion of said first named means, said second named means also being rotatable relative to revolutions thereof about an axis disposed at an angle to the axis of the tube receiving portion of said first named means, means for revolving said second named means, means for rotating said second named means during revolutions thereof, said second named means being movable longitudinally relative to said first named means, and means for moving said second named means into engagement with said tube for spinning the wall of the tube outwardly at the end thereof. 100
